FILLING-FEELER MECHANISM FOR LOOMS

Application filed August 7, 1930. Serial No. 473,620.

The invention has relation to filling-feeler devices which commonly are used in looms for the purpose of detecting the approach of substantial exhaustion of the supply of filling occupying the working shuttle upon the lay of a loom. As is well-known, such devices are employed to bring about a change in the working of a loom when the filling-supply has been reduced to a predetermined minimum, in order to guard against the occurrence, in the cloth being woven, of an incomplete or partial pick of filling which does not extend the full width of the cloth, and which will require to be removed by hand with the loom stopped, in order to avoid production of a defect in the cloth, or will reduce the value of the finished cloth if allowed to remain. In the case of looms equipped with automatic filling replenishing mechanism, the filling-feeler acts to call this mechanism into action, so as to provide thereby a fresh supply of filling upon the lay; in the case of other looms the filling-feeler acts to stop the weaving.

More particularly the invention has relation to filling-feeler devices of the side-slipping class.

Filling-feeler mechanisms of the class to which the present invention is applicable comprise, ordinarily, a side-slipping feeler-member having movement forward and rearward of the loom imparted thereto by the feeling action, conjoined with a side-slipping pivotal indicating movement, and a transmitter that is actuated by the said side-slipping movement to indicate, as it is termed, the change in the working of the loom.

The general object of the present invention is to provide an improved filling-feeler mechanism of the side-slipping class characterized by simplicity of construction and freedom from liability to get out of order, and by light and easy action.

A special aim of the invention is to provide a filling-feeler adapted to operate upon delicate and fine filling without the injury to the filling that results from the feeling action of many of the types of such devices hitherto in use. This injury, as is well-known, results from repeated impact of the

same spot of the periphery of the shuttle-contained wound mass of filling against the feeler-member. This impact takes effect many times upon the same turns of the wound mass of filling, before the supply becomes so far depleted as to begin unwinding those turns with resulting shifting of the impact to other turns underlying the original superficial turns. This localized pounding of the wound mass sometimes involves displacement of the said turns, and resulting interference with free delivery of the filling from the wound mass. Sometimes, it results in the cutting or breaking of one or more turns; or in chafing or other injury to the filling. The finer the filling the more subject it is to injury, by reason of the greater length of yarn comprising the wound mass, and its consequent longer duration in the shuttle, and also due to its delicacy and inability to withstand the repeated pounding.

The invention comprises a novel and improved side-slipping feeler device characterized by the provision of a filling-feeler having a laterally offset filling-engaging tip and pivotally mounted on a carrier which moves forward with the feeler-member as the latter is driven forward in the advance of the lay in a feeling action, and by the provision of a single resilient element acting on the feeler to hold it yieldingly erect in its presentation position, and through its action on the feeler also serving to hold the carrier that is combined with the latter yieldingly rearward and to return such carrier to its rearward position after each feeling action.

An illustrative embodiment of the invention is shown in the accompanying drawing, in which,—

Fig. 1 is a plan view of certain of the parts at the feeler end of a loom, namely a portion of the lay, a shuttle and its filling-supply, and the said embodiment.

Fig. 2 is a plan view similar to Fig. 1, showing the side-slipping indicating action of the feeler.

Fig. 3 is a side elevation of the feeler.

The improved filling-feeler device is located as usual hitherto at one end of the breast beam of the loom in which the device is em-

ployed, being supported by means of a bracket 2 applied in connection with the breast beam of the loom. To the outer end of this bracket the feeler-stand 4 is made fast by a suitable bolt 6. In the feeler-stand 4 is a feeler-carrier 7 comprising a rearward portion rectangular in section and a forward portion of reduced diameter and circular section, sliding freely forward and rearward at right angles to the lay 8 in guides formed in the vertical portions of the feeler-stand, and limited in its travel rearward by a stop-pin 9 through its forward end which projects from the stand. The feeler-carrier or slide 7 has a pivot 10 fixed in its rearward extremity, on which is pivotally mounted the feeler-member 12. This feeler-member is of the familiar side-slipping type, and has a serrated filling-engaging tip 14 offset with respect to the pivot 10 in the direction of the length of the lay 8 and the shuttle-contents 42, 44, illustrated in connection with the latter. Preferably the feeler-tip 14 is a separate piece which is united in a screw-threaded engagement with a member 16 in which is formed the hub 18 fitting freely on the pivot 10.

This portion 16 of the feeler-member 12 is provided at its frontward surface with a flattened face 20, Fig. 2, disposed at an acute angle with respect to the axis of the shank of the filling-engaging tip 14. This flattened face 20 is adapted to be engaged by a similar flattened face 22, substantially co-extensive laterally with the face 20, and disposed parallel to the lay, this flattened face 22 being formed on the rearward extremity of a resilient element 24 having a rearward portion of rectangular section sliding freely in a guide 26 formed in the feeler-stand and having a reduced forward portion of circular section freely slideable within a guide 27, also formed for its reception in the feeler-stand. The resilient action of the element 24 is derived from the arrangement of an expanding spring 28 coiled about the reduced cylindrical forward portion of the element 24 and exerting a rearward push against the shoulders 30 at the point where the shape of the element 24 changes from rectangular to circular. The forward end of the spring 28 bears at 32 against the surface of the fixed stand 4 adjacent the guideway 27 therein through which slides the reduced forward portion 55 of the element 24.

The expanding spring 28 acts to push the resilient element 24 yieldingly and resiliently rearward at all times. The flat rearward face 22 of the resilient element 24 engages and presses rearwardly against the co-acting flat surface 20 on the feeler-member 12, and by reason of such pressure normally compels the face 20 to assume a position in parallel with the face 22 and in contact with the latter surface along a line parallel to the

lay and extending laterally beyond the pivot 10 at each side of the latter. The result of the rearward push of the resilient element 24 thus normally is, first, to rotate the feeler-member 12 about its pivotal connection on the carrier 7 until the two surfaces 20 and 22 are in substantial parallelism, and thus to bring or hold the feeler-member yieldingly erect in its desired angular presentation position for engagement by the shuttle-contents as the lay advances, and secondly, to hold the feeler member and its carrier yieldingly rearward in the path of the advancing lay and to return these parts to their normal rearward position after each feeling action, through causing rearward sliding movement and permitting forward sliding movement of the carrier 7 within the feeler-stand 4.

The feeler-member is equipped with a tail 34 which extends upwardly and forwardly from the vicinity of the surface 20 on the feeler-member. Through the lateral movement of this tail incident to side-slipping of the feeler-member when the latter detects substantial exhaustion of the filling occupying the shuttle, an impulse is derived which is utilized to call the change in the operation of the loom which initiates replenishment of the supply of working filling on the lay.

The means for deriving the change-calling impulse from the side slipping movement of the feeler-member about its pivot 10 on the carrier may be of any well-known or desired form. Owing to the manifold forms now known and in common use, only a fragmentary portion of a transmitting member 36 is shown, adapted to call the aforesaid change through a pull delivered to the transmitting member by the movement of the feeler-tail substantially laterally of the loom. To engage the transmitting member 36 with the feeler-tail, a plurality of holes 38 are provided in the feeler-tail, with the desired one of which the turned-down extremity of the member 36 is engaged, and in which it is secured by a pin 40.

From the foregoing, it will be apparent that the parts are normally held in the relationship shown in Fig. 1 with the filling-engaging rearward extremity of the feeler-member presented to the impact of the shuttle-contents in oblique and offset relation to the pivot 10 by which the feeler-member is mounted on the carrier 7. When the offset extremity of the feeler-member is struck by the advancing shuttle-contents, the offset relation of the extremity tends to make the feeler-member rotate about its pivot 10, but so long as sufficient filling for continued weaving remains, the serrations at the rearward extremity of the tip 14 will be engaged by the filling and prevented from movement lengthwise of the surface of the wound mass. The feeler-member and carrier will be thrust forward with respect to the feeler-stand 4, 130

the resilient member 24 yielding to permit such forward movement, and no change in the angular presentation position of the feeler-member with attendant rotation on its pivot 10 will result. When, however, the wound mass of filling 42 approaches substantial exhaustion, and the few remaining turns thereon are no longer able to restrain the tendency of the feeler-member 12 to swing about its pivot, the parts assume the relationship shown in Fig. 2, with the filling-engaging tip slipping lengthwise along the surface of the denuded bobbin 44 and with attendant change of the angular position of the feeler-member and resulting rotation about its pivot 10, through which rotation an impulse is derived and transmitted by the transmitting member 36 to call the change.

It will be observed that when the feeler-member is in any other than its normal angular presentation position, the face 20 on the feeler-member is displaced out of parallel with its coacting face 22 of the resilient member 24. This causes the rearwardly directed force exerted by the resilient member 24 on the feeler-member, normally passing through the pivot 10, to be delivered to the feeler-member at a point that is offset laterally of the loom, with respect to the feeler-member's pivot 10 and hence this force acts to resist rotation of the feeler-member about such pivot, and acts to restore it to its normal angular presentation position whenever the feeler-member is displaced out of such position by the superior force exerted by the shuttle-contents during a side slipping detecting action. That is, in whichever direction the feeler may be displaced out of its normal presentation position through rotation about the pivot 10, immediately it is so displaced, the point of application of the force of the resilient member 24 is shifted laterally with respect to the pivot 10 to resist such rotation. Thus, the provision of the surface 20 shaped to conform to the coacting face of the resilient member 24 forms a stop-device which determines the angular presentation position of the feeler-member with respect to the carrier. To define the extreme limit of rotation permitted the feeler-member about its pivot 10 in side slipping, a stoppin 46 is provided, herein a cotter-pin, one end of which is adapted to be engaged by the surface 48 of the vertical portion of the tail 34.

The described device for feeling the filling is of important practical value. It presents an organization characterized by marked saving of wear and tear on the wound filling-supply. The moving parts of the feeler are light and easy on the filling in the repeated feeling operations, and sensitive and accurate in gauging the amount remaining, and responsive in acting to call the change. The use of the single resilient element, involving

the use of a single spring, and engaging directly with the feeler-member to effect the two results of holding and restoring the feeler-member rearward after it and its carrier have been thrust forward, and of holding and restoring the feeler-member erect in proper angular relation to receive the impact of the shuttle-contents, affords a marked advance in reducing cost and upkeep, and in simplifying repairs and adjustment.

While I have illustrated and described a certain form in which the invention may be embodied, I am aware that many modifications may be made therein by any person skilled in the art, without departing from the scope of the invention as expressed in the claims. Therefore, I do not wish to be limited to the particular form shown or to the details of construction thereof, but

What I do claim is:—

1. A filling-feeler mechanism for looms, having in combination, a feeler-carrier, a side slipping feeler-member pivotally mounted on the carrier, and resilient means exerting a force on the feeler-member in balanced relation and without tendency to produce pivotal movement of the feeler-member when in normal angular relation, and exerting a force on the feeler-member, when the latter slips sidewise, tending to produce pivotal movement opposite to that resulting from side slipping.

2. A filling-feeler mechanism for looms, having in combination, a feeler-carrier, a side slipping feeler-member pivotally mounted on the carrier and having a surface normally disposed parallel to the lay but tilted from such normal position upon the side slipping of the feeler member, a resilient element having a similarly disposed surface coacting with the first surface to hold the feeler-member against rotation about its pivot, and guide means for the resilient element serving to maintain the said surface of the latter parallel to the lay at all times.

3. A filling-feeler mechanism for looms, having in combination, a feeler-carrier, a side slipping feeler-member pivotally mounted on the carrier and having a surface disposed parallel to the lay and extending on opposite sides of the said pivotal mounting, and a resilient element having a similarly disposed and similarly extending surface coacting with the first surface to hold the feeler-member against rotation about its pivot and to hold the carrier rearward.

4. A filling-feeler mechanism for looms, having in combination, a fixed stand, a feeler-carrier slidably mounted in such stand, a side-slipping feeler-member pivotally mounted on the carrier, a member slidably mounted in the stand, and a spring forcing such latter member rearward against the tail of the feeler-member, the flat engaging surface of the

member causing the coacting surface of the tail to enter into parallelism therewith and thus determining the normal angular relation of the feeler-member about its pivot, and at 5 the same time acting to hold the feeler-member and carrier rearward in the fixed stand.
